UNITED STATES PATENT OFFICE.

CHARLES GORE, OF LOS ANGELES, CALIFORNIA.

MECHANICALLY-OPERATED SAFETY ZONE.

1,394,903.

Specification of Letters Patent.

Patented Oct. 18, 1921.

Original application filed May 29, 1920, Serial No. 385,320. Divided and this application filed January 21, 1921. Serial No. 439,001.

To all whom it may concern:

I, CHARLES GORE, a subject of the King of Great Britain, residing in the city of Los Angeles, county of Los Angeles, and State 5 of California, have invented certain new and useful Improvements in Mechanically-Operated Safety Zones, of which the following is declared to be a full, clear, and exact description, enabling those skilled in the art 10 to which it appertains to make and use the same, reference being had to the accompanying drawings, which form part of this specification.

My invention relates to safety devices 15 for street cars, and more particularly to a reciprocal plunger adapted to provide a safety zone in the manner shown in the drawings and described in the following specification and claims.

20 It being known that many serious accidents result from the carelessness of drivers of vehicles attempting to pass street cars while discharging or taking on passengers, it is an object of my invention to provide suitable 25 means to prevent, as nearly as possible, the possibility of such accidents, by providing a zone of safety, protected by a reciprocally mounted, illuminated plunger.

It is an object of my invention to cause 30 the reciprocal plunger to be operated in one direction by means of air pressure on a piston, and to cause it to be operated in the other direction by means of a spring after the air pressure has been released from the 35 cylinder.

It is a further object of my invention to cause the reciprocation of the plunger element, to open or close the motor circuit, thus preventing the street car being operated during 40 the period that the plunger mechanism is extended.

It is a still further object to provide suitable means of conveying electric current to an incandescent lamp in the end of said 45 plunger element, and to provide means of opening and closing the circuit to said incandescent lamp.

In an application filed by me May 29, 1920, Serial No. 385,320, of which this is a division, 50 I illustrate the principles of this invention. These principles are herein more fully shown and described in my preferred form.

With the foregoing objects and principles in mind, reference may be had to drawings 55 forming part of this specification and show-

ing my invention in modified form applied to a street car.

Figure 1 is an end elevation of a street car, showing my mechanism mounted thereon with a reciprocal element 10 represented in 60 the extended position by the dotted lines, and in the telescoped position by the solid line.

Fig. 2 is a longitudinal section and plan of my cylinder and plunger, means of illuminating the extended end of said plunger, and the mechanical switch for effecting control by opening and closing the main circuit to the propellent motors of the car for effecting car control, as hereinbefore set forth. 70

Fig. 3 is a cross-section through an air valve which merely represents a suitable valve for the purpose of admitting air to the cylinder 7, and allowing same to exhaust therefrom, thus enabling the spring 17 to 75 return the plunger 10 to its telescoped position.

Fig. 4 is a cross-section on the line X—X of Fig. 2.

Fig. 5 is a longitudinal section and plan of 80 a modified means of conveying electric current to the illuminating means 18 within the plunger 10.

In the figures, 6 is a street car, 7 is the cylinder mounted on said street car 6, by 85 means of the brackets 8 and 9 respectively. 10 is a reciprocal plunger mounted within the cylinder 7, and being rigidly attached to a piston 11. 12 represent anti-friction members which may be on the order of sheaves, 90 allowing the reciprocal member 10 to operate freely without resort to stuffing, boxes or lubrications. 13 represents an air valve admitting air pressure to the cylinder 7 through the passage 15 and the connection 16 with 95 the cylinder 7. 14 represents a suitable rotatable valve mounted in 13. 17 represents a spring adapted to return the piston 11 to the inner end of the cylinder 7 and there bring it into contact with a reciprocal plunger 100 23 in order to operate the same against the tension of the spring 34 thus breaking the contact at 26, thereby opening the light circuit 18 and to close contact 35 enabling the street car to be propelled. 18 is an incandescent lamp, or similar source of light for illuminating the reciprocal member 10, such illumination to be visible through apertures 19. 20 is a binding post at the end of the conductor rod 40 conveying electric current 110

to the lamp 18 from said binding post by means of the wire 20^a. 21 is an insulated copper wire for current leading through insulated sleeve 25. 22 is another similar electric lead. 23 is a reciprocal element held in position by a spring 34 and caused to operate reciprocally by the momentum of the piston 11, and by its momentum cause an oscillation of the element 28 to open contact 35 and 10 close contact 26, or vice versa. 24 represents a suitable telescopic means for conveying an electromotive force to the lamp 18. 25 is shown to be an insulating sleeve around the electric lead 21. 26 represents a contact for 15 opening and closing the circuit to the lamp 18. 27 is a means of attaching the end of the spring 17 to the cylinder head 29. 28 is a fulcrumed member attached to an oscillating member 23. 29 is a cylinder head. 30 is a 20 cap over the end of the cylinder 7. 31 is a further lead for an electromotive force from contact 26. 32 is the inlet for air pressure to the valve 13 through which it may pass to the cylinder 7. 33 is an outlet from valve 25 13 which may be placed in communication with the passage 15—16, respectively, through an oscillation of the rotary member 14. 34 is a spring on the oscillating switch element 23 and 28. 35 is a contact which 30 controls the motor circuit of the car 6. 36 is a suitable soft pad which may be pneumatic in character and is designed to prevent injury to the passengers about to board the car. Referring to means 24 of conveying an electromotive force to the lamp 18, Fig. 5 is an enlarged longitudinal section of my preferred means of conducting said electromotive force, in which 37 is a metallic tube. 38 is an insulating coating surrounding said tube. 39 is an insulating guide tube, and 40 is a metallic conductor adapted to telescope within the metallic tube 37.

From the description given, and by reference to the drawings, the construction of 45 the device will be readily understood. When the car 6 is stopped, either to take on or discharge passengers, the conductor or motorman having charge of the operation of the gate, operates the controlling device 14, and 50 by admitting air to the cylinder 7, causes the plunger 10 to extend outward, thus closing the street against vehicular traffic in proximity to the car, and forming a safety zone from which passengers may leave or 55 board the car in safety.

When the signal is given for the car to proceed, the mechanism 14 is once more operated by the conductor or motorman, and the plunger 10 is driven back into the cylinder 60 7, by means of the spring 17, the car then proceeds, the plunger remaining in that position until the car is again stopped.

It is a principle of this invention, that the 65 movement of the plunger 10 control the motor circuit of the car 6 and also the light

18 in said plunger, by means of a mechanism such as plunger 23, spring 34, fulcrumed number 28, contact 26, to the light 18, and the motor circuit 21 and 22, and contact 35.

Thus when the plunger 10 and the piston 70 11 are fully telescoped within the cylinder 7, they press against the plunger 23, overcome the tension of the spring 34, cause reciprocal movement of fulcrumed member 28, open contact 26 to the light 18, and close 75 contact 35, controlling the motor circuit of the car 6, thus allowing said car to be operated under power. The cycle, or order of events, is reversed when air is admitted to the cylinder 7 by means of rotating 14 in the 80 valve 13 to admit air to the cylinder 7, to cause the projection of the extension member 10.

I claim:

1. In combination with a street car, a 85 mechanism adapted to provide a safety zone comprising, a stationary cylinder, a reciprocal plunger mounted therein, a piston attached to said plunger, a valve to supply air pressure to one side of said piston to cause 90 the reciprocation of same against the tension of a spring, for the purpose of providing a safety zone, and in combination with said mechanism, means to illuminate the end of 95 said reciprocal member, when the same is extended, and mechanical means to open the car motor circuit while said plunger is extended, thus preventing a possible starting of said street car while the safety zone mechanism is extended.

2. In a street car safety device, the combination with the car, of a stationary cylindrical member, a piston mounted therein, a reciprocal plunger attached to said piston, means of supplying air pressure to said piston to cause said reciprocal member to project beyond the side of the car and partway into the driveway between the car and the street curb, and combined therewith mechanical means for opening the street car 110 motor circuit while said reciprocal piston and plunger are extended to prevent said car from making progress.

3. In a safety device of the character described, a car, a reciprocal member performing the functions of a gate, and adapted to partly close the street between the car and curb against vehicular traffic, a cylinder suitably attached to the car frame, air control means adapted to admit air to said cylinder and to allow of the escape of same, mechanical means in the cylinder to control the motor circuit of the car and to control a circuit for illuminating the end of said reciprocal gate as described.

4. In a device of the character described, a car, a reciprocal gate attached to the car, and adapted to partly close the street between the car and the curb against vehicular traffic, an air valve, a source of air pressure 130

supply, means to operate said air valve, and mechanical means in combination with said reciprocal gate, adapted to control the motor circuit by opening and closing same, and 5 adapted to control an illuminating circuit to a light in the end of the reciprocal gate.

5. In a device of the character described, a car, a cylinder attached thereto, a reciprocal element mounted in the cylinder and adapted 10, when extended, to provide a safety zone in proximity to the entrance to, or exit from, said car, an air valve, a source of air supply, a connection to the cylinder, means to operate said air valve for the purpose of causing 15 the reciprocation of a piston and plunger, by means of said air pressure, and in the cylinder mechanical means to control an illuminating light in the end of the plunger element, and to open and close the motor circuit of said car to prevent starting the car 20 while said plunger element is extended.

6. In a device of the character described, a car, a cylinder and plunger adapted to provide a safety zone as described, an air valve 25 to admit air to drive out said plunger, a spring adapted to return said plunger when the air is released, and mechanical means, combined with the cylinder for controlling an electric circuit to an incandescent lamp in 30 the end of the plunger, and for controlling the motor circuit of said car, by opening and

closing the same through mechanical contact with the reciprocal element.

7. In a device of the character described, a car, means to propel the car, means attached 35 to the frame of the car, as shown, adapted to project an extension member into the roadway between the car and the curb, thereby partly closing said roadway to vehicular traffic; a switch operated by the movement 40 of said extension member, and adapted to close the motor circuit of the car when in the telescoped position, and to open said motor circuit while closing an illuminating circuit 45 in the extension member, as it is caused to project into the roadway.

8. Means to provide a safety zone, as described, comprising an electrically driven car, a reciprocal extension member, adapted to open the car circuit and to close a light 50 circuit when extended, and adapted to close the car circuit, and open the light circuit when in the telescoped position, means to cause the movement of said extension member, comprising an air valve and air pipe 55 connections from said valve to the cylinder, to cause the movement in one direction, and a spring means to cause the movement in the other direction when said air pressure is released.

CHARLES GORE.
